UNITED STATES PATENT OFFICE.

THEODORE P. BROWN, OF WORCESTER, MASSACHUSETTS, ASSIGNOR TO THE SIMPLEX PIANO
PLAYER CO., OF WORCESTER, MASSACHUSETTS, A CORPORATION OF MASSACHUSETTS.

TRACKER.

No. 902,555.

Specification of Letters Patent.

Patented Nov. 3, 1908.

Application filed December 6, 1907. Serial No. 405,306

To all whom it may concern:

Be it known that I, THEODORE P. BROWN, a citizen of the United States, residing at Worcester, in the county of Worcester and State of Massachusetts, have invented a new and useful Tracker, of which the following is a specification.

It is well known that automatic musical instruments and musical instrument players which are controlled by perforated note sheets have usually been made so as to sound only sixty-five of the notes of an ordinary piano, but of late, it has been thought desirable to provide means whereby the whole eighty-eight notes may be sounded. In order to do this, it is of course necessary to provide a tracker with eighty-eight note channels instead of sixty-five and to connect them up in a way similar to what has been done before. The main objection to this is, that entirely new sets of note sheets will have to be provided and the old ones cannot be used on the new instruments. In order to avoid this, several propositions have been made for providing tracker bars with two or more sets of channels so that note sheets constructed to control different numbers of notes on the instrument may be used on the same device.

The principal object of the present invention is to provide improved means whereby a plurality of different kinds of note sheets may be used on the same instrument, the mechanism for opening and closing the two or more sets of note channels being located out of sight, preferably within the tracker, or at any rate, in such position that it will not readily be noticed, and to provide an exceedingly simple and inexpensive arrangement for alternately opening the several sets of note channels.

Further objects and advantages of the invention will appear hereinafter.

Reference is to be had to the accompanying drawings which show one form in which the invention may be carried out and in which,

Figure 1 is a front elevation of the end of a tracker box showing a preferred form of the invention. Fig. 2 is a transverse sectional view of the same.

In order to accomplish the desired result, the tracker box 10 is provided with a tracker 11 or a pair of trackers, as may be desired, having a plurality of sets of note channels 12

and 13. The channels of each of these sets are separated from each other by spaces which are of substantially the same length as the channels themselves, at least not shorter than the channels.

The number of channels in each set may be varied at will, but the invention is illustrated as applied to an instrument in which there are sixty-five channels 12 and eighty-eight channels 13. The channels 12 are connected up in the usual way by tubes or passages 16 which are preferably staggered in order to get them into the small space provided in the tracker. The channels 13 are similarly connected by tubes or passages 17 with the tubes or passages 16 so far as may be permitted by the number of the latter. In other words, sixty-five of the channels 13 which correspond with the sixty-five channels 12 are connected with them so as to produce the same striking effect. Of course, there are twenty-three additional channels 13 which are not connected with any of the channels 12 but which are connected with pneumatic actions in the usual or any desired way.

Now, in order to provide for controlling the two sets of channels, a pair of reciprocable slides 40 and 41 are employed. These slides preferably move longitudinally with respect to the tracker so that they may be located in a convenient position and may be so constructed as to take up very little space. The slide 40 is provided with perforations 42 corresponding with the channels 12. In the same way, the slide 41 is provided with perforations 43 corresponding with the tubes 17. There are also spaces 44 and 45 between the several perforations 42 and 43 respectively, these spaces being at least as long as the perforations so that they will cover up or close the passages or channels in which they are located when the slides are moved so as to bring the perforations out of registration with the channels or passages.

The slides are mounted in passage ways or grooves 46 and 47 respectively. In this case these passage ways are shown as of dovetailed shape and are at the front of the tracker so that the two slides are in sight and constitute the surfaces over which the note sheet travels. Each of these slides may in either case be operated independently, but it is preferred to operate them together so that when one is moved to close one set of passages the other will be moved to open the

other. For this purpose a lever 48 is connected with the two slides, being housed within the tracker and being pivoted between them, one arm of the lever being longer than the other for the same purpose as above. When one slide is moved in one direction, the other is thereby caused to move in the opposite direction in the form shown. In this case, also, no other mechanism need be employed for moving them as they can be reciprocated by means of thumb notches in their front sides. The sides 51 of the tracker box, may conveniently serve as stops to prevent the slides moving beyond a certain point and to avoid the necessity of adjusting them each time they are shifted.

It will be seen that this invention is capable of being carried out in a very simple way so as to avoid any complicated mechanism such as has been used heretofore and also to avoid changing the appearance of the tracker itself. Furthermore, the constructions which can be employed for carrying out the invention are very simple in form and inexpensive. It is to be observed, also, that a portion of the invention may be used even on ordinary instruments which do not have double trackers, as one of the slides can be employed alone to open and close the channels of an ordinary tracker when it is desired to prevent the operation of an instrument which has to be left in a public place.

The mechanism is so simple that it can be entirely hidden from view and persons unaccustomed to the particular instrument would not be able to operate it if the instrument were left with the channels closed.

While I have illustrated and described a preferred form of the invention, I am aware that many modifications may be made therein by any person skilled in the art without departing from the scope of the invention as expressed in the claims. Therefore, I do not wish to be limited to the particular form shown, but

What I do claim and desire to secure by Letters-Patent is:—

1. A tracker for a musical instrument having two sets of channels and provided with a pair of longitudinally reciprocable slides dove-tailed into the front of the tracker, said slides having passages communicating with the tracker channels.

2. A tracker for musical instruments having at the top thereof a pair of reciprocable slides, each flush with the front of the tracker, said slides having channels therein, those in one slide being wider than those in the other, and means whereby when one slide is moved in one direction the other will be moved in the opposite direction.

3. In a tracker, the combination of a block having tracker channels therethrough, a pair

of slides dove-tailed into the front thereof and flush with the front surface of the tracker, said slides having notches in their front surfaces, whereby they may be manipulated by hand from the front of the tracker, and means inside the tracker for moving one slide when the other is reciprocated.

4. In a tracker the combination of a block having a plurality of series of tracker channels, a front plate having a plurality of dove-tailed grooves, a slide in each of said grooves having passages adapted to communicate with said channels, means whereby said slides can be manipulated from the front, and a lever pivoted near the front of said tracker back of said slides and pivotally connected with said slides, whereby said slides will be caused to reciprocate simultaneously.

5. The combination with a tracker, of a block having tracker channels therethrough, a pair of slides flush with the front surfaces of the tracker, said slides having means whereby they may be manipulated by hand from the front of the tracker, and means inside the tracker for moving one slide when the other is reciprocated.

6. A tracker having channels therein, a pair of slides adapted to close said channels, said slides having means whereby they may be manipulated by hand, and means inside the tracker for moving one slide when the other is moved.

7. A tracker for a musical instrument, having channels and provided with a longitudinally reciprocable slide dove-tailed into the front of the tracker flush with the front surface thereof, said slide having passages communicating with the channels: 100

8. A tracker for a musical instrument, having channels and provided with a longitudinally reciprocable slide dove-tailed into the front of the tracker flush with the front surface thereof, said slide having passages communicating with the channels and said tracker having spaces for limiting the motion of said slide in the position in which said passages register with the channels.

9. A tracker having channels therein, a pair of slides adapted to close said channels, said slides having means whereby they may be manipulated by hand, means inside the tracker for moving one slide when the other is moved, and stops on the ends of the tracker for engaging said slides and limiting their motion in both directions.

In testimony whereof I have hereunto set my hand, in the presence of two subscribing witnesses.

THEODORE P. BROWN.
